US00D693550S

(12) **United States Design Patent**
Montross et al.

(10) **Patent No.:** US D693,550 S
(45) **Date of Patent:** ** Nov. 19, 2013

(54) **SHOE**

(71) Applicant: **Reebok International Limited**, London
(GB)

(72) Inventors: **Matthew Montross**, Middleboro, MA
(US); **Ricardo Vestuti**, Providence, RI
(US)

(73) Assignee: **Reebok International Limited**, London
(GB)

(**) Term: **14 Years**

(21) Appl. No.: **29/444,725**

(22) Filed: **Feb. 1, 2013**
